UNITED STATES PATENT OFFICE.

MAXIMILIAN KLEIN, OF NORTH PLAINFIELD, NEW JERSEY, AND JOHN A. STEIN, OF NEW YORK, N. Y., ASSIGNEES TO AMERICAN MACHINE AND FOUNDRY COMPANY, OF NEW YORK, N. Y., A CORPORATION OF NEW JERSEY.

TIP-APPLYING MACHINE.

Application filed September 6, 1924. Serial No. 736,247.

To all whom it may concern:

Be it known that we, MAXIMILIAN KLEIN and JOHN A. STEIN, citizens of the United States, residing, respectively, at North Plainfield, in the county of Middlesex and State of New Jersey, and New York, in the county and State of New York, have invented a new and useful Improvement in Tip-Applying Machines, of which the following is a specification.

This invention relates to an improved tip-applying machine, particularly adapted for use in connection with a cigarette machine of the continuous-rod type, in which tips 15 of cork or other suitable material are applied to a constantly traveling strip of paper which becomes the wrapper of the cigarette rod and of the individual cigarettes cut therefrom.

In tip-applying machines heretofore used for the purpose above mentioned, the tips have been applied to the constantly traveling strip of paper while they were traveling in the same direction and at the same speed 20 as said strip. The application of the tip to the strip of paper was usually effected by a rolling contact of the tip support with the traveling strip, and the time available for pressing together the tip and the strip was 25 so short that the tips sometimes failed to stick to the strip. When this occurred, it would not be discovered until after the tipless part of the strip of paper had passed through the cigarette machine and became 30 a cigarette wrapper. Customarily, the tip material, as applied to the strip of paper, was wide enough for two tips and the cut which severs the rod into individual cigarettes was made through the middle of the 35 applied tip, so that a part of the material would form the tip of another cigarette. Whenever the tip material failed to stick to the strip or was imperfectly attached thereto, two cigarettes would have to be destroyed because the misplaced tip or lack of tip would not be discovered 40 until after the cigarette rod had been cut up into individual cigarettes. The cause of the difficulty, and a remedy therefor, has now been discovered and this discovery forms the subject matter of the present invention, the main object of which is the production of a machine for applying tips to a constantly traveling strip, whether

or not the said strip be a strip of paper to be used as a cigarette wrapper, comprising mechanism for intermittently arresting minor parts of said strip, and mechanism for applying tips to the arrested parts, preferably by simultaneously pressing together all parts of the tip and an arrested part of the strip. A further object is the production of a machine of the character above indicated in which the tip material is given a slow and continuous movement in a path which crosses the path of the traveling strip, in order to avoid the difficulties encountered in tip-applying machines heretofore used, wherein the tip material was given an intermittent movement. With this and other objects not specifically mentioned in view, the invention consists in certain constructions and combinations of elements which will be hereinafter fully described and then specifically set forth in the claims hereunto appended.

In the accompanying drawings, which form a part of this specification and in which like characters of reference indicate the same or like parts, Fig. 1 is a front elevation, partly in section, of a machine constructed in accordance with the invention; Fig. 2 is an end elevation, also partly in section, of the structure shown in Fig. 1; and Fig. 3 is a sectional view, on an enlarged scale, taken on the line 3—3 in Fig. 1.

In carrying the invention into effect, there is provided a machine for applying tips to a constantly traveling strip, comprising mechanism for intermittently arresting minor parts of said strip in order to gain time within which tips may be applied to said parts without interrupting the constant travel of the major part of the strip, and mechanism for applying tips to the arrested parts.

In the best constructions, the arresting mechanism is operative to successively arrest said parts, and the applying mechanism is operative to successively apply tips to said parts, although in certain constructions a plurality of parts of the strip may be simultaneously arrested and a plurality of tips may be simultaneously applied thereto; the arresting mechanism is cam-actuated and the applying mechanism is in part continuously operative and in part intermittently operative; the arresting mechanism includes

stationary and movable strip-guiding devices and means for producing reciprocations of said movable devices in the path of said strip; and the applying mechanism includes 5 means for advancing an adhesive tip ribbon in a path crossing the path of said strip, and means for severing a tip from said ribbon and pressing together said tip and said strip at said crossing.

10 The foregoing parts may be widely varied in construction within the scope of the claims, for the particular machine selected to illustrate the invention is but one of many possible concrete embodiments of the 15 same. The invention therefore is not to be restricted to the precise details of the structure shown and described.

Referring to the drawings, S indicates a constantly traveling strip, as of cigarette 20 wrapping paper, which is unwound from a reel, as shown at the right in Fig. 1, and traveling toward the left in that figure, its motion being produced by the rod forming mechanism of a cigarette machine when the 25 present machine is used in connection with such cigarette machine. It is to be understood, however, that the use of the present invention is not restricted to use in connection with a cigarette machine, for the present 30 machine may be used for applying labels or the like to a constantly traveling strip of material for other purposes.

Mechanism is provided for intermittently 35 arresting minor parts of the strip S without interrupting the constant travel of the major part thereof, in order that time may be gained within which a tip or label may be applied to the strip. As shown, this mechanism includes stationary strip-guiding devices or rollers 4 and 5 and movable strip-guiding devices or rollers 6-6. Means are 40 provided for producing reciprocations of the movable strip-guiding rollers 6-6 in the path of the strip S. This means is cam-actuated and includes a slide 7, carrying the rollers 6-6 and reciprocating in slideways 8-8 supported by the frame 9 of the machine. The slide 7 is reciprocated by means 45 of a link 10, one end of which is stationarily pivoted at 11 to the slide 7, its other end being pivoted at 12 to a block 13 slidably mounted in an arm 14 carried by a short shaft 15 journaled in the frame 9. The shaft 15 carries an arm 16 which is connected by means of a link 17 with a bell-crank 18-19 fulcrumed on a bar 20 supported by the frame 9. The arm 19 of the bell-crank 18-19 carries a bowl 21 running on the perimeter of a cam 22 fast on a 50 shaft 23, which is the main cam shaft of the machine. The cam bowl 21 is held in contact with the perimeter of the cam 22 by means of a tension spring 24 of well-known construction and operation. The cam 55 shaft 23 is driven by a gear 25 which is fast

thereon and which is driven by a pinion 26 fast on a short shaft 27 which also carries a bevel gear 28 driven by a similar bevel gear 29 splined on a power shaft 30 having a clutch mechanism generally indicated by the 70 reference character 31 and of well known construction and operation.

By the mechanism just described, reciprocations of the slide 7 are produced alongside the path of the strip S, and the cam 22 75 is so formed that the rearward movement of the slide 7, and of course of the strip-guiding rollers 6-6, is equal to the forward movement of the strip S when the minor operation of said strip extending from the 80 roller 6 to the other roller 6 is to be arrested for the application of a tip or other device to said strip.

Cigarette machines of the standard type 85 are capable of making cigarettes of different sizes by simple readjustment. When the present invention is to be used in connection with a cigarette machine, the readjustment of the cigarette machine necessitates readjustment of the tip-applying machine and 90 means are therefore provided for varying the amplitude of the reciprocations of the slide 7 and movable strip-guiding rollers 6-6 which are carried thereby. It will be remembered that one end of the link 10 is 95 pivoted to the block 13 which is slidable in the arm 14. The block 13 is moved by means of an adjusting screw 32 rotatably mounted in a bearing 33 formed on the upper part 100 of the arm 14, the threaded part of the screw being in engagement with a boss 34 formed on the block 13. The means for varying the amplitude of the reciprocation of the slide 7 and strip-guiding rollers 6-6 is therefore screw-actuated, and when the point 12, 105 at which one end of the link 10 is pivoted to the block 13, is moved upwardly or toward the axis of the shaft 15, the reciprocations of the slide will be shortened, as when shorter cigarettes are to be tipped. 110 Inversely, when the said point is moved away from the axis of the shaft 15, the reciprocations of the slide and strip-guiding rollers 6-6 will be lengthened, as when longer cigarettes are to be tipped. 115

However the movement of the constant- 120 traveling strip S is produced, the mechanism so far described operates to intermittently arrest minor parts of said strip so that tips or other material may be applied thereto, as desired.

Mechanism is provided for applying tips to the arrested parts of the strip S. This mechanism includes a tip support adjacent the path of the strip and an arrested part of said strip, the pressure being simultaneously applied to the entire surface of the tip and the tip being severed from an adhesive tip ribbon marked R, drawn from a 125 reel, as at the right in Fig. 2, and advanced 130

to a position adjacent the path of the strip S. As shown, the tip support includes a suction turret generally indicated by the reference character 35, provided with a series 5 of suction apertures 36 through its periphery, and with an interior suction chamber 37 in communication with said apertures and with a pipe 38 connecting the chamber 37 with a suitable suction producing mechanism, not shown but of well known construction and operation. The suction chamber 37 is held in contact with a portion of the inner periphery of the turret 35 by the action of two springs 39 bearing against said 10 chamber and against two abutments 40, the latter being adjustably secured to the frame of the machine. The tip ribbon R is held by suction on the upper left-hand quarter of the turret 35, as seen in Figs. 2 and 3, and 15 the turret is given a slow rotating movement to advance the tip ribbon R to a position adjacent the path of the strip S and in a path crossing the path of the strip S at the point where a minor part of said strip is 20 arrested. For the purpose of giving the turret this slow movement, it is mounted on a shaft 41, being held thereon by means of a tapered bearing and thumb screw 42. The shaft 41 is journaled in suitable bearings 25 in a frame 43 slidably mounted in the frame 9, the frame 43 being movable vertically by means of an adjusting screw 44, having an operating knob 45 at the top of the machine, the purpose of this adjustment 30 being to permit the use of different sized suction turrets when different sized cigarettes are to be made, or different widths of tip material are to be used.

The shaft 41 carries a bevel gear 45^a in 35 mesh with and driven by a similar bevel gear 46, the latter being fast on a shaft 47 journaled in the frame 43 and in a second frame 48 secured to the main frame 9. When the frame 43 is raised or 40 lowered to effect a change of suction turrets, the shaft 47 will be raised or lowered with it. Splined to this shaft within the frame 48 is a worm wheel 49 through which the shaft 47 may slide. The worm wheel 49 is driven by a worm 50, the latter being 45 fast on the end of the cam shaft 23 before described. By means of the mechanism just described, the suction turret 35 is given a very slow but continuous movement to advance the tip ribbon R into position adjacent 50 the path of the strip S in order that the tip material may be applied to an arrested part of said strip.

When a tip ribbon is used, however, it is 55 necessary to sever an individual tip therefrom for application to the strip S, and means is provided for this purpose. The said means includes a knife 51 adjustably mounted on a frame 52, the latter being fast on a short shaft 53 journaled in the frame 9 and

rocked by means of an arm 54 connected by means of a link 55 with a cam lever 56, fulcrumed in the bar 20 before referred to. This cam lever carries a bowl 57 running on the periphery of a cam 58 fast on the cam 70 shaft 23 before referred to. The bowl 57 is held to its duty by means of a tension spring 59 of well known construction and operation. The contour of the cam 58 is such that the knife 51 descends rapidly to 75 sever a tip from the ribbon R at the moment that the rearward movement of the slide 7 and movable strip-guiding rollers 6-6 is equal to the forward movement of the strip S; or in other words, at the moment that the arrested part of the strip S is in 80 position to have a tip applied thereto. Coacting with the knife 51 are a series of shear blades 60 secured to the turret 35.

It is desirable that the tip severed from 85 the ribbon R be applied to the strip S at the same time that it is severed from the ribbon, and means is provided for this purpose. With this end in view, the arm 52 carries not only the knife 51 but a pressure pad 90 61 of suitable material, such for example as rubber, the pad being secured to a metallic holder 62 mounted on a stem 63 slidable in a boss formed on the free end of the arm 52. A spring 64 is interposed between the holder 95 62 and the boss of the arm 52 through which the stem 63 slides. The thrust of the spring 64 is limited by means of locked nuts 65 threaded on the end of the stem 63 above the boss of the arm 62. As the cam 58 causes 100 the arm 52 to rapidly descend, the pad 61, which normally overlies the path of the strip S, engages the arrested part of the strip and forces it down upon the end of the adhesive tip ribbon which has been brought into position just below the path of the strip S. When the pad 61 thus presses together a tip 105 on the suction turret 35 and an arrested part of the strip S, further movement of the arm 52 causes the knife 51 to sever from the ribbon that part of the same then pressed against the arrested part of the strip, the yield of the spring 63 permitting this further movement of the arm 52 and increasing the pressure on the now assembled tip and 110 strip. This pressure is applied to the whole surface of the tip and although its application is but momentary, it is sufficient to cause the tip to permanently adhere to the strip without danger of displacement while the 115 adhesive is drying or becoming set. The rotating movement of the turret 35 is so slow, and the application of the pressure to the assembled tip and strip is so short, that 120 no wrinkling of the tip occurs.

Means are provided for applying adhesive 125 to the tip ribbon R, and this means includes a paste receptacle 66 hinged at 67 to a frame 68 carrying a paste applying roller 69 mounted on a shaft 70 journaled in the 130

frame 68 and carrying a gear 71 driven by another gear 72 fast on a short shaft 73 driven by worm gearing 74 deriving its motion from the shaft 47 before referred to. 5 The paste receptacle 66 is provided with a feed roller 75 supported by cone pivots 76 and 77 and partly submerged in paste within the receptacle. The feed roller 75 is rotated by its contact with the paste applying roller 10 69, the latter being positively driven as hereinbefore described. The tip ribbon R runs under idle rollers 78 supported by the frame 68 and runs over the paste applying roller 69. Thus paste is applied to the tip ribbon 15 69 as it is advanced to position to be applied to the strip S. It is desirable, however, that when the machine is stopped for any reason, the paste applying means be incapacitated and then rehabilitated when 20 the machine is again started up, the purpose of this being to prevent an irregular accumulation of dried paste on the paste applying rollers 69. With this end in view, means are provided for incapacitating and 25 rehabilitating the paste applying means, and this incapacitating and rehabilitating means consists of a frame 79 slidable on bars 80-80 within the frame 68 and carrying studs 81 adapted to engage and lift the tip ribbon 30 from the periphery of the paste applying rollers 69 when they are moved to the position shown in dotted lines in Fig. 2, to prevent the ribbon from sticking to the temporarily stationary roller. In order that this 35 movement of the studs 81 may be effected automatically, the incapacitating and rehabilitating means includes a bell-crank 82 suitably fulcrumed at 83 and engaging a bar 84 reciprocated by the operating lever 85 of 40 the clutch mechanism 31 before referred. The bar 84 also engages a lever 86 suitably fulcrumed at 87, the lever 86 being connected to a bell-crank 88 suitably fulcrumed at 89, the free end of the bell-crank 88 being in engagement with the lip 90 formed on one wall 45 of the paste receptacle 66. When declutching occurs, the connections just described operate to lift the studs 81 from the position shown in full lines to the position shown in dotted lines in Fig. 2, and to lower the paste 50 receptacle from the position shown in full lines to the position shown in dotted lines in the same figure; thus separating the paste feed roller and the paste applying roller and 55 also the paste applying roller and the tip ribbon. It will be readily understood that when reclutching occurs, the parts will again be brought to the position shown in full lines in Fig. 2, and the paste applying mechanism will be rehabilitated.

In certain constructions within the invention, it may be necessary to produce a relative readjustment of the strip-guiding rollers 4 and 5 to compensate for warpage of the strip, as when the latter is damp. As shown,

this relative adjustment is effected by adjusting the strip-guiding roller 4 which is mounted in a yoke 91 fulcrumed on a screw 92 threaded into the frame of the machine. The yoke 91 extends beyond the screw 92, 70 and the extended part of the same engages one end of an adjusting screw 93 threaded through an upright 94 rising from a slide 95. The extended end of the yoke 91 is held against the adjusting screw 93 by means of a tension spring 96 of well known construction and operation. The slide 95 may be longitudinally moved by means of an adjusting screw 97 rotatable in a depending lug 98 formed on the slide 95, the screw 97 being threaded into the frame of the machine. By the mechanism just described, the strip-guiding roller 4 may be moved toward and away from the strip-guiding roller 5; and by means of the adjusting screw 93, the strip-guiding roller 4 may be swung slightly on its screw fulcrum 92 when the condition of the strip requires such adjustment to cause the strip to run true over the several guiding rollers. 90

An additional stationary strip-guide may be employed to accurately position the strip adjacent the point where a tip is applied to an arrested part of said strip. Such a guide is shown in Figs. 1 and 2 and consists of a 95 channeled strip 99 engaging the strip S between the guiding-rollers 6-6. This channeled strip is clamped by means of a screw 100 to an arm 101 fulcrumed on a stud 102 and held in position vertically by means of 100 a set screw 103 which engages a V-groove 104 in an arm extending rearwardly from the stud 102. The lever 101 and stud 102 have a sidewise adjusting movement to adjust the strip S sidewise, both lever and stud being movable in one direction by the action of a thumb screw 105, and in the other direction by the action of a spring 106, the latter being interposed between the lever 101 and the right-hand slideway 8 before 110 referred to, which supports the stud 102.

In view of the foregoing, a detailed description of the operation of the device is deemed to be unnecessary and is therefore omitted in the interest of brevity. 115

What is claimed is:

1. A machine for applying tips to a constantly traveling strip, comprising mechanism for intermittently arresting minor parts of said strip, and mechanism for applying tips to the arrested parts. 120
2. A machine for applying tips to a constantly traveling strip, comprising mechanism for intermittently arresting minor parts of said strip, and mechanism for applying tips to the arrested parts, said arresting mechanism being operative to successively arrest said parts, and said applying mechanism being operative to successively apply tips to said parts. 125

3. A machine for applying tips to a constantly traveling strip, comprising mechanism for intermittently arresting minor parts of said strip, and mechanism for applying tips to the arrested parts, said arresting mechanism being cam-actuated. 70
4. A machine for applying tips to a constantly traveling strip, comprising mechanism for intermittently arresting minor parts of said strip, and mechanism for applying tips to the arrested parts, said arresting mechanism including movable strip-guiding devices, and means for producing reciprocations of said devices along the path of said strip. 75
5. A machine for applying tips to a constantly traveling strip, comprising mechanism for intermittently arresting minor parts of said strip, and mechanism for applying tips to the arrested parts, said arresting mechanism including movable strip-guiding devices, and means for producing reciprocations of said devices along the path of said strip. 80
6. A machine for applying tips to a constantly traveling strip, comprising mechanism for intermittently arresting minor parts of said strip, and mechanism for applying tips to the arrested parts, said arresting mechanism including movable strip-guiding devices, and cam-actuated means for producing reciprocations of said devices along the path of said strip. 85
7. A machine for applying tips to a constantly traveling strip, comprising mechanism for intermittently arresting minor parts of said strip, and mechanism for applying tips to the arrested parts, said arresting mechanism including movable strip-guiding devices, means for producing reciprocations of said devices along the path of said strip, and means for varying the amplitude of said reciprocations. 90
8. A machine for applying tips to a constantly traveling strip, comprising mechanism for intermittently arresting minor parts of said strip, and mechanism for applying tips to the arrested parts, said arresting mechanism including movable strip-guiding devices, a slide carrying said devices, an arm, a link stationarily pivoted to said slide and adjustably pivoted to said arm, and means for oscillating said arm. 95
9. A machine for applying tips to a constantly traveling strip, comprising mechanism for intermittently arresting minor parts of said strip, and mechanism for applying tips to the arrested parts, said arresting mechanism including stationary and movable strip-guiding devices, means for relatively adjusting said stationary devices, a slide carrying said movable devices, an arm, a link stationarily pivoted to said slide and adjustably pivoted to said arm, and cam-actuated means for oscillating said arm. 100
10. A machine for applying tips to a constantly traveling strip, comprising mechanism for intermittently arresting minor parts of said strip, and mechanism for applying tips to the arrested parts, said applying mechanism being in part continuously operative and in part intermittently operative. 105
11. A machine for applying tips to a constantly traveling strip, comprising mechanism for intermittently arresting minor parts of said strip, and mechanism for applying tips to the arrested parts, said arresting mechanism including stationary strip-guiding devices, and screw-actuated means for relatively adjusting said devices. 110
12. A machine for applying tips to a constantly traveling strip, comprising mechanism for intermittently arresting minor parts of said strip, and mechanism for applying tips to the arrested parts, said arresting mechanism including movable strip-guiding devices, a slide carrying said devices, an arm, a link stationarily pivoted to said slide and adjustably pivoted to said arm, and means for oscillating said arm. 115
13. A machine for applying tips to a constantly traveling strip, comprising mechanism for intermittently arresting minor parts of said strip, and mechanism for applying tips to the arrested parts, said arresting mechanism including stationary and movable strip-guiding devices, means for relatively adjusting said stationary devices, a slide carrying said movable devices, an arm, a link stationarily pivoted to said slide and adjustably pivoted to said arm, and cam-actuated means for oscillating said arm. 120
14. A machine for applying tips to a constantly traveling strip, comprising mechanism for intermittently arresting minor parts of said strip, and mechanism for applying tips to the arrested parts, said applying mechanism including a tip support adjacent the path of said strip, and means for pressing together a tip on said support and an arrested part of said strip. 125
15. A machine for applying tips to a constantly traveling strip, comprising mechanism for intermittently arresting minor parts of said strip, and mechanism for applying tips to the arrested parts, said applying mechanism including a tip support adjacent the path of said strip, and means for pressing together a tip on said support and an arrested part of said strip. 130
16. A machine for applying tips to a constantly traveling strip, comprising mechanism for intermittently arresting minor parts of said strip, and mechanism for applying tips to the arrested parts, said applying mechanism including a tip support adjacent the path of said strip, and cam-actuated means for pressing together a tip on said support and an arrested part of said strip.
17. A machine for applying tips to a constantly traveling strip, comprising mecha-

- 6
- nism for intermittently arresting minor parts of said strip, and mechanism for applying tips to the arrested parts, said applying mechanism including means for advancing an adhesive tip ribbon to a position adjacent the path of said strip, and means for there severing a tip from said ribbon and pressing together said tip and an arrested part of said strip.
18. A machine for applying tips to a constantly traveling strip, comprising mechanism for intermittently arresting minor parts of said strip, and mechanism for applying tips to the arrested parts, said applying mechanism including a suction turret for advancing an adhesive tip ribbon to a position adjacent the path of said strip, means for there severing a tip from said ribbon and pressing together said tip and an arrested part of said strip, and means for slowly and continuously rotating said turret.
19. A machine for applying tips to a constantly traveling strip, comprising mechanism for intermittently arresting minor parts of said strip, and mechanism for applying tips to the arrested parts, said applying mechanism including means for advancing an adhesive tip ribbon to a position adjacent the path of said strip, a cam-actuated knife for there severing a tip from said ribbon, and means for pressing together said tip and an arrested part of said strip.
20. A machine for applying tips to a constantly traveling strip, comprising mechanism for intermittently arresting minor parts of said strip, and mechanism for applying tips to the arrested parts, said applying mechanism including means for advancing a tip ribbon to a position adjacent the path of said strip, means for there severing a tip from said ribbon, and cam-actuated means for pressing together said tip and an arrested part of said strip.
21. A machine for applying tips to a constantly traveling strip, comprising mechanism for intermittently arresting minor parts of said strip, and mechanism for applying tips to the arrested parts, said applying mechanism including means for advancing a tip ribbon to a position adjacent the path of said strip, and means for applying paste to said ribbon.
22. A machine for applying tips to a constantly traveling strip, comprising mechanism for intermittently arresting minor parts of said strip, and mechanism for applying tips to the arrested parts, said applying mechanism including means for ad-
- vancing a tip ribbon to a position adjacent the path of said strip, means for applying paste to said ribbon, and means for incapacitating and rehabilitating said pasting means.
23. A machine for applying tips to a constantly traveling strip, comprising mechanism for intermittently arresting minor parts of said strip, and mechanism for applying tips to the arrested parts, said applying mechanism including means for advancing a tip ribbon to a position adjacent the path of said strip, means for applying paste to said ribbon, a clutch controlling the machine operation, and connections between said clutch and said paste applying means for incapacitating said paste applying means when declutching occurs and for rehabilitating said paste applying means when reclutching occurs.
24. A machine for applying tips to a constantly traveling strip, comprising mechanism for intermittently arresting minor parts of said strip, and mechanism for applying tips to the arrested parts, said applying mechanism including means for advancing an adhesive tip ribbon in a path crossing the path of said strip, and means for severing a tip from said ribbon and pressing together said tip and an arrested part of said strip at said crossing.
25. Mechanism for intermittently arresting minor parts of a constantly traveling strip, comprising stationary and movable strip-guiding devices, and means for producing reciprocation of said movable devices along the path of said strip.
26. Mechanism for intermittently arresting minor parts of a constantly traveling strip, comprising stationary and movable strip-guiding devices, means for relatively adjusting said stationary devices, and means for producing reciprocations of said movable devices along the path of said strip.
27. Mechanism for intermittently arresting minor parts of a constantly traveling strip, comprising stationary and movable strip-guiding devices, means for relatively adjusting said stationary devices, means for producing reciprocations of said movable devices in the path of said strip, and means for varying the amplitude of said reciprocations.

In testimony whereof, we have signed our names to this specification.

MAXIMILIAN KLEIN.
JOHN A. STEIN.
